UNITED STATES PATENT OFFICE.

CURT J. ROHLAND, OF PROVIDENCE, RHODE ISLAND, ASSIGNOR TO NATIONAL RING TRAVELER CO., OF PROVIDENCE, RHODE ISLAND, A CORPORATION OF RHODE ISLAND.

FASTENING.

1,306,279.

Specification of Letters Patent. Patented June 10, 1919.

Application filed October 14, 1918. Serial No. 257,943.

To all whom it may concern:

Be it known that I, CURT J. ROHLAND, a declarant citizen of the United States, heretofore a subject of William II, Emperor of 5 Germany, residing at Providence, county of Providence, State of Rhode Island, have invented certain new and useful Improvements in Fastenings, of which the following is a specification.

10 This invention relates to fastenings or the like provided with a head of material different from the shank as for example, a head of papier mâché, leather or fiber.

My invention in its most usual embodiment is in the form of an upholstery nail or tack and will be more particularly discussed in that form although obviously capable of application to other articles of manufacture. The great difficulty heretofore in the 20 manufacture of articles of this sort has been to effect an attachment of the head to the shank with sufficient permanence to avoid its disruption in driving or in drawing.

In such forms of these articles as are provided with head of fiber it has been exceedingly difficult on account of the nature of the head to secure anything like a substantial permanence because of the common tendency of the head to pull away from the metal 30 shank. Various forms of expanding or clenching connectors have been used but have been so far as I am advised, of necessity, made so that they would bend easily in clenching and therefore equally liable to bend and give away under strain.

The object of my invention is to provide such an article headed in such a manner as to secure a maximum strength of attachment and yet capable of being produced rapidly 40 and economically.

This I accomplish by rotatively embedding in a disk of mill board, the head of the nail which has been given a general spiral form so that it be entered readily and lodged with 45 great security. The practice of my invention will be more fully set forth in the specification which follows in which I shall describe a form well adapted to practical use and convenient manufacture.

50 The form shown in the drawings is characteristic of my invention although only one of many. Throughout drawings and specifications like reference characters are em-

ployed to indicate corresponding parts. In the drawings:

55

Figure 1 is a view of an upholstery nail with attached head in section.

Fig. 2 an elevation of the headed end of the nail member.

Fig. 3 face and edge views of the head 60 blank.

Fig. 4 a plan view of the headed end of the nail member.

Fig. 5 an elevation of the finished article and

65

Fig. 6 a sectional view of the head attached but before finishing.

In practising my invention I produce headed fastening members of any desired type as for example the nail shown in the 70 drawings. Each such fastening consists of a shank 1 headed at 2. The head is preferably rather thin and is radially opened up with a sector shaped cut as at 3. The cut is made on somewhat of a bevel to give two 75 rather sharp edges which are oppositely sprung. This forms of the disk a warped surface of the general class of flat spirals, the disk like head however pitching oppositely about the line of the shank 1.

The head 4 is prepared in blank from 4^a being a simple disk cut from suitable mill board stock which preferably has somewhat of transverse strata as suggested in the section shown in Fig. 6.

80

In practice the prepared fastenings are fed to a rotatable chuck in which they are grasped and rotated against the center of the face of a blank 4^a. As each blank is fed it therefore receives a shank head which 90 is rotatively lodged within it. In this lodgment the upper edge of the slit 3, being warped bites into the face of the blank on a radial line and works successively through the strata until it is completely embedded 95 in the center of the blank.

The rough head is finished by compression into the shapes required and this compression of the head condenses the structure of mill board to a comparatively 100 homogeneous mass with the warped head definitely set in its center.

Nails headed in this manner show a remarkable degree of permanency as to their heads and may be driven and drawn without dislodging or disrupting the head.

The fastenings may be of various types and the heads may be variously produced and fashioned. The manner of assembly may also be varied and the practice of the invention modified all without departing from the spirit of my invention if within the limits of the appended claims.

What I therefore claim and desire to secure by Letters Patent is:

- 10 1. A fastening of the class described comprising a head and a shank having a headed end comprising a flat spiral embedded in said head.
- 15 2. A fastening of the class described comprising a head and a shank having a headed end comprising a single turn flat spiral embedded in said head.
- 20 3. A fastening of the class described, comprising a compressible head, and a shank having a head provided with a radial slit and embedded in said head.
- 25 4. A fastening of the class described, comprising a transversely laminated fiber head, a shank having a relatively thin head provided with a radial slit and embedded in the laminations of said compressible head.
5. A fastening comprising an attached head, and a shank having a flattened slotted

head embedded in said attached head, the edges of the slit lying in different planes. 30

6. The method of making a headed fastening consisting in slitting the head, in oppositely warping the edges of said slit and in embedding the slit head in a covering head by a rotative progression. 35

7. The method of making a headed fastening, consisting in slitting said head, in warping one edge of the slit from the plane of the other edge, in embedding the head in a covering head by a rotative progression, 40 and in subsequently compressing said covering head thereon.

8. The method of making a headed fastening, consisting in radially slitting the head, in spreading the slit transversely of the 45 plane of the head, in embedding said split head in a laminated fibrous covering head by a rotative progression through the laminations, and in subsequently compressing 50 said covering head thereon.

In testimony whereof I affix my signature in presence of two witnesses.

CURT J. ROHLAND.
